UNITED STATES PATENT OFFICE.

PATRICK KEEGAN, OF LOWELL, MASSACHUSETTS, ASSIGNOR TO DRAPER CORPORATION, OF HOPEDALE, MASSACHUSETTS, A CORPORATION OF MAINE.

WARP STOP MOTION FOR LOOMS.

Application filed July 17, 1922. Serial No. 575,523.

To all whom it may concern:

Be it known that I, PATRICK KEEGAN, a citizen of the United States, and resident of Lowell, county of Middlesex, State of Massachusetts, have invented an Improvement in Warp Stop Motions for Looms, of which the following description, in connection with the accompanying drawing, is a specification, like characters on the drawing representing like parts.

This invention relates to warp stop motions for looms and more particularly to means for indicating the location of a dropped detector and the broken or abnormally loose warp thread, which has caused the loom to stop, so that the operator may readily locate and piece or place in proper condition the warp thread and start the loom.

It is common to provide looms with warp stop motions comprising a series of detectors supported by the warps and so arranged that, when one of the warps breaks or slackens unduly, the detector supported by it drops and effects the actuation of mechanism which stops the loom.

It is a difficult matter for the operator to locate such a dropped detector and broken or abnormally loose warp because of the very large number of warps in the sheet and the inconspicuous character of the detectors. Various means have, therefore, been devised in an effort to enable the operator readily to locate the dropped detector and thus to minimize the loss of time required in piecing the broken warp or taking up the slack and starting the loom.

The present invention employs a familiar type of thin, flat detectors, normally supported in parallelism and close together in one or more banks, and provides means manually operated after the loom is stopped for twisting a dropped detector out of parallelism with the other detectors. Thus the detectors and the warps are separated by the twisted detector and the location of the latter is made obvious.

The invention in another feature utilizes a means for positively grasping the dropped detector by its edges to effect the stopping of the loom, and preferably for this purpose a pair of parallel bars which have imparted to them by a moving part of the loom a relative lateral reciprocation whereby the dropped detector is grasped by its edges be-

tween them. The invention in a preferred form provides in connection therewith a means manually operated after the loom is stopped for giving a relative longitudinal movement to the bars thereby to twist the dropped detector grasped there between and thus render the location of the dropped detector obvious.

These and other objects and features of the invention will appear more fully from the accompanying description and will be particularly pointed out in the claim.

In the drawings:

Fig. 1 is a view, partly in side elevation, and partly in vertical section, of a sufficient portion of a loom to illustrate a preferred embodiment of the invention;

Fig. 2 is a front elevation of that portion of the stop motion mechanism directly concerned with the present invention;

Fig. 3 is a side elevation, partly in vertical section of the construction shown in Fig. 2;

Fig. 4 is a top view enlarged of a small section of one of the banks of the detectors and the warps corresponding thereto;

Fig. 5 is a view similar to Fig. 4 showing a dropped detector in twisted position with portions of the grasping bars by which the twisting action is secured in a preferred form of the invention.

A simple and preferred embodiment of the invention is illustrated in the accompanying drawings as applied to the well known "Northrop" type of loom and as utilizing a well known type of stop motion mechanism, but it will be understood that the broad principles of the invention may be embodied in other types of looms and in other types of stop motion mechanisms.

The loom illustrated comprises the usual side frames 1 and 2, breast beam 3, lay 4, main shaft 5, cam shaft 6, harness frames 7, and other usual parts.

The detecting portion of the stop motion mechanism is mounted in a suitable position in the rear of the harness frames at the top of the loom. For that purpose supporting brackets 8 extend upwardly from the loom sides. These brackets are connected by the longitudinal parallel flat bars 9 extending transversely of the loom directly beneath the warp sheet. The warps as they pass from the warp beam, not shown, to the shed forming mechanism rest upon and are supported by the upper edges of these bars at

opposite sides of the detectors. If, as herein illustrated, there is more than one bank of detectors, intermediate supporting rods 10 are provided to support the warps between the banks of detectors.

The detectors are in the form of thin, flat metal pieces 11. Each detector is provided with a small aperture 12 through which its warp passes so that normally each detector is supported by the warp with the apertures 12 in the same plane as the top surfaces of the bars 9 and the rod 10. The detectors are guided so as to move vertically by means of long vertical slots 13 formed therein and fitting over flat, vertically disposed detector guide bars 14 extending transversely of the loom between the supports 8.

The detectors are shown as arranged in two banks extending transversely of the loom, and this is a preferred and familiar arrangement, but it may be varied as desired.

A flat plate or bar 15 provided with a serrated rearward edge 16 extends transversely of the loom beneath the forward edges of the forward bank of detectors, and for that purpose is conveniently secured to the forward supporting bar 9. A similar bar 17 provided with a serrated edge 18 is mounted in a corresponding location at the bottom of the rear supporting bar 9. A feeler bar or plate 19 having serrated edges 20 and 21 extends parallel with the bars 15 and 17 and is so mounted as to rock toward and from these bars. For that purpose the feeler bar 19 is conveniently supported by arms 22 secured to and extending upwardly from a rock shaft 23. This rock shaft is supported in bearings 24 carried by brackets 25 adjustably secured to the supporting bars 9 and is given a rocking or oscillating movement from a continuously moving part of the loom such as the cam shaft 6. As the mechanism for giving this rocking or oscillating movement is well known and familiar, it needs no further description.

If the rocking or oscillating movement of the shaft 23 is restrained, this mechanism acts to move the link 26 endwise, thus rocking the shipper actuating lever 27 pivotally mounted at 28 on the loom frame and provided with a cam slot 29 engaging the shipper lever 30. When this endwise movement of the link 26 takes place, the shipper lever 30 is thrown out of engagement with its usual retaining slot causing the stoppage of the loom, in a manner well known to those skilled in the art.

The general type of mechanism illustrated between the oscillating feeler bar 19 and the shipper lever 30 is similar to that disclosed in Letters Patent No. 673,824 granted to Stimpson May 7, 1921.

It will be seen that the bars 15 and 19 are parallel and extend longitudinally of

and beneath the opposite edges of the front bank or series of detectors and that the mechanism provided acts to give relative lateral reciprocation to said bars by reason of the oscillation of the movable bar 19 with respect to the fixed bar 15. If now a warp breaks and a detector in the front bank drops, these longitudinally extending bars 19 and 15 grasp the dropped detector by its edges and thereby effect the stopping of the loom in the usual manner. In the similar way the bars 19 and 17 cooperate with the rear bank or series of detectors.

The serrated edges of the grasping bars prevent the twisting of the dropped detector prior to the stopping of the loom and insure the arresting of the operating movement of the shaft 23 which in this form of mechanism is utilized to effect the stopping of the loom.

The present invention provides means for shifting the grasping means to twist a dropped detector out of parallelism with the other detectors. This twisting movement is effected by moving the rocking or oscillating bar 19 longitudinally with respect to the opposing fixed bar, or in other words, by giving a relative longitudinal movement to said bars.

A preferred form of mechanism for thus twisting the dropped detector after the loom is stopped, is illustrated in detail in Figs. 2 and 3. Supporting brackets 31 and 32 are secured to and depend from the warp supporting bars 9 to provide at their lower ends below the shaft 23 bearings for the ends of a rock shaft 33. A bifurcated arm 34 is secured by means of set screws 35 to the shaft 33 and projects upwardly with the bifurcated ends in engagement with the end surface of a collar 36 forming a portion of the arm 22. Another arm 37 is secured to and extends out from the shaft 33 along side of the rear bracket 31. At its free end the arm 37 is pivoted to the lower end of a rod 38, mounted as by means of guide eye 39 to move vertically at the rear face of the rear supporting bar 9. The upper end of the rod 38 is provided with a suitable handle 40. A helical spring 41 is mounted on the shaft 23 between the collar 36 and the bearing 24. A stop lug 42 on the bracket arm 32 serves to limit the upward movement of the arm 37.

The parts of the mechanism are normally in the position illustrated in Figs. 2, 3 and 4. The spring 41 holds the shaft 23 and consequently the serrated edge bar 19 in fixed relation longitudinally of the fixed serrated edge bars 15 and 17 because this spring presses the collar 36 against arm 34 which is held rigid by reason of the engagement of the arm 37 with the stop lug 42. When the loom is in operation the shaft 23 is continually rocked or oscillated by the mech-

- anism of the loom, already described, and consequently the bar 19 is constantly moved toward and from the fixed bars 15 and 17 or, in other words, a relative lateral reciprocation is constantly taking place between the bar 19 and the bar 15 and between the bar 19 and the bar 17. If now a warp breaks the detector 11 supported thereby drops, and if it is in the front bank its 10 lower end comes between the serrated edges of the bar 19 and the bar 15 while if it is in the rear bank its lower end comes between the serrated edges of the bar 19 and the bar 17. Immediately this takes place the serrated edge bars grasp the dropped detector 15 by its edges, the rocking movement or later reciprocation of the bar 19 is restrained and the loom is stopped through the operation of the mechanism already described.
- 20 In order now to locate the position of the dropped detector, the operator presses down on the handle 40 thus swinging the arm 37 downwardly away from the stop 42, rocking the shaft 33 and the bifurcated arm 34 and thus moving the shaft 23 longitudinally 25 against the tension of the spring 41, and thus giving a relative longitudinal movement between the serrated edge bars by which the dropped detector is grasped.
- 30 This causes the dropped detector to be twisted out of parallelism with the other detectors and into a position substantially as shown in Fig. 5. The twisting of the dropped detector separates the bank or series 35 of parallel detectors to a noticeable degree so that the location of a dropped detector is at once apparent, and the warp associated therewith may be pieced or its slack taken up.
- 40 The detecting mechanism, it will be observed, is manually operated so that the dropped detector may be held in twisted position for as long as necessary to locate its position and make the necessary repairs.
- 45 This detecting mechanism is not operated until after the loom is stopped so that no undue strain is placed upon the dropped detector, and its full strength is available in the stopping of the loom because when it is grasped by the serrated edge bars to effect the stopping of the loom, the grasping action is applied in the plane of the detector.
- It will be apparent that, among other things, the position of the handle 40 and the location and construction of the particular mechanism for effecting longitudinal movement of the shaft 23 and for maintaining it normally in position may be varied widely from the illustrated construction.
- The invention provides a very simple and efficient mechanism readily adaptable to existing forms of stop motion mechanism for effecting the desired results.
- Having thus explained the nature of the invention and described a preferred embodiment thereof, although without attempting to set forth all of the forms in which it may be embodied and used, what is claimed is:
- A warp stop motion for looms comprising a series of flat warp detectors normally supported in parallelism by the warps, a pair of parallel bars extending longitudinally of the edges of the series of detectors, means operated by a moving part of the loom to give a relative lateral reciprocation to said bars and cause them to grasp a dropped detector by its edges and thereby effect the stopping of the loom, a vertically movable handle rod mounted for vertical movement on a fixed part of the loom and extending upwardly above the warp sheet into a convenient position to be reached by the operator, and a lever connection between said handle rod and said bars acting upon movement of the handle rod to effect a relative longitudinal movement of the said bars whereby upon the movement of the handle rod by the operator after the loom is stopped the dropped detector will be twisted out-of 75 parallelism with the other detectors thereby 80 to indicate the position of the dropped detector.
- In testimony whereof, I have signed my name to this specification.

PATRICK KEEGAN.
